J. J. GREENWALD,
WINDOW SCREEN.
APPLICATION FILED AUG. 30, 1919.

Patented July 27, 1920.

UNITED STATES PATENT OFFICE.

JACOB JOSEPH GREENWALD, OF SHEBOYGAN, WISCONSIN.

WINDOW-SCREEN.

1,347,946.

Specification of Letters Patent. Patented July 27, 1920.

Application filed August 30, 1919. Serial No. 320,803.

To all whom it may concern:

Be it known that I, JACOB J. GREENWALD, a citizen of Bavaria, residing at Sheboygan, in the county of Sheboygan, State of Wisconsin, have invented certain new and useful Improvements in Window-Screens; and I do hereby declare the following to be a full, clear, and exact description of the invention, such as will enable others skilled in the art to which it appertains to make and use the same.

This invention is an improvement in window screens, and has particular reference to a fly guard therefor.

The object of the invention is to provide an improved screen of simple and inexpensive construction made in sections adapted to be assembled edge to edge in numbers sufficient to close the sash opening, the upper section being made in such a manner that the window may be entirely or partially opened without the liability of flies and other insects entering the house.

The inventive idea involved is capable of receiving a variety of mechanical expressions, one of which for the purpose of illustrating the invention, is shown in the accompanying drawing wherein:

Figure 1 is a general perspective view of the window screen showing the same in position in a window frame.

Fig. 2 is a perspective view of the screen sections slightly separated.

Fig. 3 is a transverse section on the line 3—3 of Fig. 1.

Referring more particularly to the drawings, F indicates the frame in which the sashes U and L are slideable in the usual manner, and G is the glass or pane of the lower sash.

The window screen which comprises the essential feature of this invention is adapted to be mounted adjacent the lower sash L in such a manner as to permit of the raising of said sash to open the window, and said screen must be of a size to close the opening exposed by said sash so as to prevent the ingress of flies and other insects into a room when the sash is in its raised position. For this purpose a pair of vertical guides are secured to the sides of the frame F, and each consists of a base plate 7 secured to the frame by suitable fasteners 8 such as screws, and a pair of vertically disposed guide strips 9 secured to the plate 7 so as to be disposed at right angles thereto and in parallel re-

lation with and spaced from each other. To this end each strip 9 is formed upon its edge with a plurality of spaced tongues 10 which are extended through slots in the plate 7 and then bent over upon the plate to secure the strip in its proper position.

The screen body is slidably mounted between the guide strips 9 and said body preferably comprises the two screen sections 12 and 13 and the upper or guard sections 14, respectively. The lower and intermediate sections 12 and 13 each preferably comprises a metallic frame 15 of U-shaped formation to which is secured the wire netting sheet 16. The upper rail is composed of two spaced strips 17 projecting above the side bars to form a groove 18 for receiving the lower rail of the next superposed frame, and suitable fasteners 19 may be passed through the strips and side bars to secure the same together.

The upper section 14 of the screen is also preferably formed U-shaped and of metal, and when the section is in position the side bars thereof will engage between the guide strips 9 in the same manner as the side bars of the frame 15 engage therein. The upper section 14 is provided with a guard lip 20 formed by cutting the material of the section 14 upon vertical lines to a depth substantially equal to one-half of the depth of the section. These cuts are spaced to give the lip a length equal to the distance between the inner vertical edges of the side bars of the lower window sash L, and when in its proper position the lip is bent toward and into contact with the pane of glass G in the sash L so as to prevent the insects from crawling upward on the pane and past the free longitudinal edge of the lip, and thereby gaining access to the room. The resiliency of the metal of which the lip is made may be sufficient to retain the same against the pane of glass when the window is opened and closed, but in order to aid in maintaining such contact small spring fingers 21 may be carried by the lip and project beyond its ends behind the guide strips 9. When the guard section 14 is lifted out these fingers slip off the guides; then the screen sections 13 and 12 may be removed to clean the glass G or to store the screen during the winter. But while the parts are in place the lip of the upper section serves constantly as a fly guard, though permitting adjustment of the lower sash to any desired degree.

In the drawings I have shown this window screen made up of three sections where of the lowermost numbered 12 is large, the intermediate section numbered 13 is smaller, 5 and the uppermost section 14 is that carrying the fly-guard; but it will be understood that the screen could be made or could be used with a larger or smaller number of sections. The uppermost section shown herein 10 is preferably always employed so that its lip will close the space between the plane of the netting and the glass G in the nearest sash, and in fact this section might be used at the top of any fly screen whose upper rail did 15 not perform this service. Of course the remainder of the structure might be in one section, provided the size of the sash opening and the wishes of the user were known, but even then access to the lower sash when 20 raised would not be easy. It is preferred to make the screen in two or perhaps more sections, first because they can be assembled in quantities and sizes sufficiently to close various-sized sash openings, second because 25 they can be assembled in the same window to make a tall or a short screen at different times as the user desires, and third because with at least one smaller section 13 just beneath the guard section, it is an easy matter 30 to slip out such guard and smaller section at any time in order to reach the lower rail of the lower sash and adjust it, and then restore the sections. When they are in place their sheets of netting stand in one plane 35 and are so maintained because the lower rail of the section constitutes a tongue entering the groove which is formed by spacing the upper rail of the section below; and this tongue-and-groove connection between the 40 sections renders the use of light guides possible since their only function is to hold the sections upright.

What is claimed is:—

1. The herein described window screen made up of a plurality of screen sections 45 superposed edge to edge with their netting sheets in a single plane, each section including a U-shaped metallic frame having its upper rail composed of two strips secured to its side bars and spaced to receive the 50 lower rail of the frame above, and an uppermost section having a guard lip deflected out of said plane and adapted to contact with the glass of the adjacent sash; combined with guides in which all sections are 55 removably mounted, as described.

2. In a window screen structure, the combination with upright guides adapted to be secured within the window frame; of a screen made up of screen sections whose 60 side rails are slidably mounted in said guides, the sections being maintained edge to edge therein with their netting sheets in a single plane, an uppermost section having a guard lip deflected out of said plane, and 65 spring fingers secured to the lip and extending beyond its ends and adapted to be engaged behind said guides.

3. The herein described fly-guard structure for window screens, the same comprising a frame section adapted to be mounted in the screen guides above the screen proper, a lip held at its lower edge within said section and adapted to be deflected out of the plane of the screen, and yielding means for 75 holding it so deflected with its free edge in contact with the glass of the adjacent sash.

In testimony whereof, I affix my signature, in the presence of two witnesses.

JACOB JOSEPH GREENWALD.
